CLAIM

The ornamental design for lens and connectors, as shown and described.

DESCRIPTION

FIG. 1 is a front perspective view of a lens and connectors;

FIG. 2 is a front elevational view of the lens and connectors of FIG. 1;

FIG. 3 is a top plan view of the lens and connectors of FIG. 1;

FIG. 4 is a rear elevational view of the lens and connectors of FIG. 1;

FIG. 5 is a bottom plan view of the lens and connectors of FIG. 1; and,

FIG. 6 is a left side elevational view of the lens and the left connector of FIG. 1.

The lens is shown separately in FIGS. 1-6 for ease of illustration only. The broken lines in FIGS. 1 and 6 are for illustrative purposes only and forms no part of the claimed design.

FIG. 1

FIG. 2
